BOTTLE OR SIMILAR ARTICLE

Franco Polime, Chappaqua, N. Y.

Application August 5, 1949, Serial No. 4,327

Term of patent 14 years

(Cl. D58—8)

To all whom it may concern:

Be it known that I, Franco Polime, a citizen of the United States, residing at Chappaqua, in the county of Westchester and State of New York, have invented a new, original, and ornamental Design for a Bottle or Similar Article, of which the following is a specification, reference being had to the accompanying drawings, forming part thereof.

Fig. 1 is an elevational view of a bottle or similar article, showing my new design, the stopper for the right hand neck of the bottle being shown as removed therefrom; and,

Fig. 2 is a top plan view of the bottle with the stoppers removed for convenience of illustration.

I claim:

The ornamental design for a bottle or similar article, substantially as shown.

FRANCO POLIME.
